UNITED STATES PATENT OFFICE.

SIEGFRED MARCUSSEN, OF MILWAUKEE, WISCONSIN, ASSIGNOR TO IMPERIAL KNITTING COMPANY, OF MILWAUKEE, WISCONSIN, A CORPORATION OF WISCONSIN.

DESIGN FOR A KNITTED CAP.

Application filed June 25, 1928. Serial No. 27,269. Term of patent 14 years.

To all whom it may concern:

Be it known that I, SIEGFRED MARCUSSEN, a citizen of Denmark, residing at Milwaukee, in the county of Milwaukee and State of Wisconsin, have invented a new and original and ornamental Design for Knitted Caps, of which the following is a specification, reference being had to the accompanying drawing, forming part thereof.

In the drawing, Fig. 1 is a side view in outline showing my new design for knitted cap, a portion of the view showing the arrangement of the different knitted stitches used in forming the entire design; and Fig. 2 is a front view thereof with the knitted stitches shown in a similar manner. The detailed illustration of the design of the several areas shown in Figures 1 and 2 continues throughout the extent of said areas.

I claim:

The ornamental design for a knitted cap, as shown and described.

SIEGFRED MARCUSSEN.
